2 SHEETS—SHEET 2.

UNITED STATES PATENT OFFICE.

JOHN A. McDONALD AND WILLIAM McDOWALL, OF CENTURY, FLORIDA.

INVALID-BED.

1,046,830.

Specification of Letters Patent. Patented Dec. 10, 1912.

Application filed March 24, 1908, Serial No. 485,396. Renewed May 1, 1912. Serial No. 894,524.

To all whom it may concern:

Be it known that we, JOHN A. McDONALD and WILLIAM McDOWALL, citizens of the United States, both residing at Century, in the county of Escambia and State of Florida, have invented certain new and useful Improvements in Invalid-Beds, of which the following is a specification.

This invention comprehends certain new and useful improvements in beds of that type designed particularly for invalids' use and the invention has for its object an improved article of this character which embodies a peculiar arrangement of parts whereby a central portion of the bed is rendered susceptible of being lowered out of position so as to have a bed pan or other desired receptacle placed thereon, the bed portion being adapted to be then raised to support the pan in convenient position to afford toilet facilities without the necessity of disturbing the patient to place the bed pan in position in the customary manner.

A further object of the invention is an improved bed bottom constructed with a central removable section which is supported on a traveling frame or carriage running in a track suspended below the bed bottom, novel mechanism being employed to admit of the bottom section being raised or lowered upon the traveling frame, according as desired.

With these and other objects in view, as will more fully appear as the description proceeds, the invention consists in certain constructions, arrangements and combinations of the parts that we shall hereinafter fully describe and then point out the novel features thereof in the appended claims.

For a full understanding of the invention and the merits thereof, and to acquire a knowledge of the details of construction, reference is to be had to the following description and accompanying drawings, in which:

Figure 1 is a perspective view of a bed constructed in accordance with our invention. Fig. 2 is a fragmentary top plan view of the bed bottom. Fig. 3 is a vertical longitudinal section on the line 3—3 of Fig. 2. Fig. 4 is an enlarged perspective view showing the removable section and traveling frame in juxtaposition. Fig. 5 is a frag-

mentary detail view showing the removable section locked in position.

Corresponding and like parts are referred to in the following description and indicated in all the views of the drawings by the same reference characters.

Referring to the drawings, the numeral 1 designates a bed bottom which may be of any desired or approved construction or design, although in the present instance it consists of a suitable rectangular frame that is covered with wire fabric. This bed bottom is formed with a preferably framed central opening 2 extending therethrough. A relatively stationary track is disposed horizontally between the opposite sides of the bed bottom and extends beneath the opening 2. The track comprises substantially parallel guide rails 3 that are suspended substantially horizontally from the bed bottom through the instrumentality of hangers 4, the guide rails being provided at their inner or opposing sides with channels extending longitudinally thereof.

A carriage or traveling frame 5 fits between the guide rails and is received in the channels thereof, and is movable in such channels, between stops 6 placed at the opposite ends of the rails to insure against the traveling frame becoming accidentally detached. Carried by and movable vertically upon the traveling frame, is a removable bed bottom section 7 that is adapted to be raised to assume a position in the central opening 2 and substantially in the plane of the bed bottom 1. The section 7, is, of course, similar in structure to the bed bottom, and, therefore, in the present instance consists of a frame 8 which corresponds in size and shape with the opening 2 and is covered with wire fabric. One or more guide rods 9 depend from the frame 8 and are arranged to slide through bosses 10 provided on the traveling frame 5, so as to guide the section in its vertical movement.

As the preferred means for raising and lowering the bed bottom section, we employ a vertically disposed rack bar 11, which is secured at its upper end to a cross bar 12 of the frame 8, and projects downwardly through the traveling frame and is engaged by a pinion 13 fixed upon an actuating shaft 14. The actuating shaft extends trans-

versely and is journaled in bearings 15 provided on the frame 5, the end portions of the actuating shaft projecting beyond said frame and terminating in knobs 16 that are arranged in convenient reach from the respective sides of the bed and render the device capable of ready manipulation.

5 A substantially U-shaped strap embraces the rack bar and the pinion and has its end 10 portions journaled on the shaft so as to prevent the shaft against sliding longitudinally in the bearings 15. The pinion 13 is thus maintained at all times in engagement with the rack bar, while the shaft is rendered 15 susceptible of being drawn in the direction of the track to cause the carriage to travel relatively thereto.

In order to effectually guide the section 7 into position in the opening 2, the frame 20 around the latter has secured thereto a plurality of guide strips 17 which project downwardly and outwardly, as best shown in Fig. 3, and are adapted to have the bottom section ride thereon upon its elevation.

25 After being moved into the opening, the section is designed to be locked in position therein so as to be maintained against downward displacement and to hold the traveling frame against movement along the track.

30 For this purpose we preferably employ a lever 18 that is fulcrumed near its middle point on the cross bar 12 and projects laterally below the bed bottom with its extremities terminating at the opposite sides thereof.

35 Two spring catches 19 are connected to the latch bar on opposite sides of the fulcrum point and are slidably mounted in corresponding rails of the frame 8 and are adapted to be projected therebeyond into 40 engagement with the framework around the opening, the catches being retracted by rocking the lever in one direction.

In the use of a bed equipped with our improved mechanism, the mattress 20 which 45 is placed upon the bed bottom 1, is constructed with a central removable section 21 that corresponds in size and shape with the bed bottom section 7 and is arranged to be normally supported thereby. In the event 50 of the necessity of providing the invalid with toilet facilities, the lever 18 is rocked in the requisite direction to retract the catches 19 from engagement with the bed bottom 1 and thus release the section 7. The 55 operator then grasps one of the knobs 16 and turns the actuating shaft so as to lower the bottom section 7 upon the traveling frame 5, said operation also displacing the mattress section 21 which is lowered to 60 together with the bottom section. The actuating shaft is drawn transversely to slide the traveling frame 5 in the track and toward one side of the bed in order to afford 65 convenient access to the bottom section 7 and admit of the mattress section 21 being

removed therefrom and replaced by a bed pan or some other desired receptacle. The foregoing operation is then reversed, whereupon the bottom section 7 is returned to place in the opening 2 and the bed pan is supported in the central opening in the mattress so as to be arranged in convenient relation to the invalid. After the use of the bed pan, the manner of removing the same and returning the mattress section to 75 position, will be obvious.

70 From the foregoing description in connection with the accompanying drawings, it will be apparent that we have provided an improved invalid's bed, by means of which a bed pan or the like may be placed in position and removed, as desired, without the necessity of disturbing the invalid, which may be advantageously employed in hospitals or the like, which is capable of 80 being easily and quickly operated, and which consists of comparatively few parts that may be easily and cheaply manufactured and are not likely to get out of order.

85 The invention further comprehends the provision of suitable means for maintaining the mattress against displacement on the bed bottom so as to prevent the section 21 from becoming shifted out of registry with the central opening 2, such object being attained in the present instance by forming the frame 8 and the frame around the opening 2 with up-standing flanges 22.

90 Having thus described the invention what is claimed as new is:

100 1. An invalid bed including a bed bottom having a central opening, a relatively stationary track disposed substantially horizontally beneath the bed bottom and extending beneath the opening, a carriage independent of the bed and mounted to travel along the track and movable to a position beneath the opening, and a removable bed bottom section independent of the bed and carried by and movable vertically upon the carriage and adapted to be supported in the 105 said opening.

110 2. An invalid bed including a bed bottom having a central opening, a relatively stationary track disposed substantially horizontally beneath the bed bottom and extending beneath the opening, a carriage independent of the bed and mounted to travel along the track and movable to a position beneath the opening, a removable bed bottom section carried by and movable vertically upon the carriage and adapted to be supported in the said opening, and means carried by the carriage and independent of the bed for moving said section vertically.

115 3. An invalid bed including a bed bottom having a central opening, a track disposed below the bed bottom and extending beneath the opening, a carriage mounted to travel along the track and movable to a position 120

tion beneath the opening, a removable bed bottom section carried by and movable upwardly above the carriage and adapted to be supported in the said opening, and means 5 for both moving the carriage along the track and moving the section upwardly above the carriage.

4. An invalid bed including a bed bottom having a central opening, a track disposed 10 below the bed bottom and extending beneath the opening, a carriage mounted to travel along the track and movable to a position beneath the opening, a removable bed bottom section carried by and movable upwardly above the carriage and adapted to be supported in the said opening, and a shaft carried by the carriage and movable in the direction of the track to cause the carriage to travel along the same, the shaft 15 being rotatable to effect the upward movement of the section.

5. An invalid bed including a bed bottom having a central opening, a track disposed below the bed bottom and extending beneath 25 the opening, a carriage mounted to travel along the track and movable to a position beneath the opening, a removable bed bottom section carried by and movable upwardly above the carriage and adapted to 30 be supported in the said opening, a rack bar secured to the section, a pinion meshing with the rack bar, and a shaft mounted on the carriage and having the pinion fixed thereon, the shaft being rotatable to effect 35 the upward movement of the section and being movable in the direction of the track to cause the carriage to travel therealong.

6. An invalid bed including a bed bottom having a central opening, a relatively stationary track disposed horizontally below 40 the bed bottom and extending beneath the opening, a carriage mounted to travel along the track and movable to a position beneath the opening and provided with a bearing, 45 a removable bed bottom section carried by and upon the carriage and adapted to be supported in the said opening, a rack bar secured to the section, a pinion meshing with the rack bar, a shaft journaled in the bearing, 50 and having the pinion fixed thereon and rotatable to effect the vertical movement of the section, the shaft being disposed in the direction of the track, and means for holding the shaft against longitudinal movement 55 through the bearing whereby to retain the pinion in engagement with the rack bar

and to permit the shaft to be drawn in the direction of the track to cause the carriage to travel along the same.

7. An invalid bed including a bed bottom 60 having a central opening, a relatively stationary track disposed substantially horizontally below the bed bottom and extending beneath the opening, a carriage independent of the bed and mounted to travel 65 along the track and movable to a position beneath the opening, a removable bed bottom section independent of the bed and carried by and movable vertically upon the carriage and adapted to be supported in the 70 said opening, and means depending from the bed bottom around the opening to guide the section therein in its upward movement.

8. An invalid bed including a bed bottom having a central opening, a track disposed 75 substantially horizontally below the bed bottom and extending beneath the opening, a carriage mounted to travel along the track and movable to a position below the opening, a removable bed bottom section carried 80 by and having a guided vertical movement upon the carriage and adapted to be supported in the said opening, and a catch engaging between the bed bottom and the section to retain the latter against downward 85 displacement from the opening and to hold the carriage against movement along the track.

9. An invalid bed including a bed bottom having a central opening, a track disposed 90 substantially horizontally below the bed bottom and extending beneath the opening, a carriage mounted to travel along the track and movable to a position below the opening, a removable bed bottom section carried 95 by and having guided vertical movement upon the carriage and adapted to be supported in the said opening, a catch engaging between the bed bottom and the section to maintain the latter against downward 100 displacement from the opening and to hold the carriage against movement along the track, and means mounted on the section for releasing the catch.

In testimony whereof we affix our signatures in presence of two witnesses.
